UNITED STATES PATENT OFFICE.

HERVEY H. MCINTIRE, OF SOUTH BEND, INDIANA.

ATTACHMENT FOR PHOTOGRAPHIC-PRINTING APPARATUS.

No. 895,034.

Specification of Letters Patent.

Patented Aug. 4, 1908.

Application filed September 11, 1903. Serial No. 172,760.

To all whom it may concern:

Be it known that I, HERVEY H. MCINTIRE, a citizen of the United States, residing at South Bend, in the county of St. Joseph and State of Indiana, have invented certain new and useful Improvements in Attachments for Photographic-Printing Apparatus; and I do hereby declare the following to be a full, clear, and exact description of the invention, such as will enable others skilled in the art to which it appertains to make and use the same.

This invention relates to improvements in apparatus for printing photographs.

It is not usual in the photographic art in negative making that the light is handled to always get a balanced negative,—that is, the relative details in the shadowed portion of the negative are out of balance with the relative details in the light part of the negative, thus rendering what is known as "charcoal and chalk" photographs, which are void of normal qualities. This occurs more in the hands of the inexperienced and less artistic operator and the present invention is designed to overcome this difficulty by providing means for adjusting the light relative to the negative, so that the light may be moved to a position opposite the densely developed portion of the negative, and the actinic rays caused to be emitted directly upon such portion, and thus give normal results in the finished photograph.

With these objects in view, the present invention consists in the construction, combination and operative arrangement of parts, all as will be more fully described hereinafter, illustrated in the accompanying drawings and finally pointed out in the appended claims.

In the drawings: Figure 1 is a view in longitudinal section of the case or cabinet with the lamps mounted therein, the latter being shown in dotted lines as adjusted to different positions. Fig. 2 is a plan view of the light adjusting means; and Fig. 3 is a vertical section on the line x—x of Fig. 2.

Making renewed reference to the drawings, wherein similar reference notations indicate like parts appearing in the several illustrations, 1 designates the case or cabinet having an inclined face board 2, provided with an opening, the edges of which are formed with an offset flange 3, on which is detachably mounted a ground glass or support 4 for the

negative 5. Hinged to the top of the inclined face board is a platen 6 adapted to be raised for the insertion of a sensitized element which is placed upon the negative and held thereto by the platen when the latter is lowered. In the front of the case is formed a hinged door 7 which permits access to the light compartment 8 beneath the ground glass 4. In the case is a horizontal partition 9, which constitutes the lower wall of the light compartment. In this partition are formed a plurality of circular openings 10 in which are mounted the lamp-supporting balls or members 11. These lamp-supporting members preferably consist of spheres which are seated in the openings 10 and formed with a diametrical bore through which the lamp-rods 12 pass. The lamp-rods 12 are loose in the bores of the spheres, so that they may be moved longitudinally to bring the lamps, which are designated by 13, nearer or further away from the negative, as desired; and thus the lamps are vertically adjustable in the case. It will thus be seen that the lamp rod constitutes one of the supports for the lamps.

To maintain the lamps in their vertically adjusted position, each supporting member or sphere is formed with an opening 14, which is disposed at right angles to the bore and rod 12, and in this opening is mounted a spring-pressed pin 14 which frictionally engages the rod 12, and which is held against displacement by a plug 15 screwed within the opening and closing the outer end thereof. By this construction, it will be apparent that the lamp with the rod may be moved vertically within the support 11 by a positive force, but will be prevented from dropping by means of the frictional contact of the pins 14. It will also be seen that the lamp may be adjusted longitudinally with respect to the negative, as the sphere with the lamp supported thereby may be moved in the socket formed by the opening 10, and these different adjustments are indicated in dotted lines in Figs. 1 and 3. It will also be seen that any number of lamps may be employed and that each lamp is universally and independently adjustable, so as to permit some portions of the negative to be acted upon by stronger rays than other portions, so that when the sensitized element or photographic paper is subjected to chemical action, chem-

ideal reduction in the photographic paper takes place in accordance with the intensity of such light rays; that is, some parts of the photographic paper are printed faster than other parts thereof.

In order to hold the lamps and their supports in their adjusted positions with respect to their swinging movements and to prevent displacement of the spheres, there is fixed to the partition 9 upon each side of each socket a pair of spring arms 16, the free ends of which engage with the surface 17 of the sphere 11 and bear with sufficient pressure thereon to prevent the lamps from being displaced by gravity or jar.

By the construction above set forth, it will be seen that the lamps have a universal movement in the light compartment and this "universal movement" is not limited to the swinging movements of the lamps with respect to the negative, but also includes movements rectilinear longitudinally or at substantially right angles to the negative, wherefore the operator is enabled to adjust the lamp to any position with relation to the negative. When it is desired to specially treat or operate upon a certain portion of the negative, the lamp may be moved back and forth within the zone of the portion to be treated in a plane parallel to the negative, notwithstanding the fact that it requires a combined oscillatory and rectilinear movement of the lamp, because the axis of the rod traverses the axis of the sphere. Thus, this parallel swing is conveniently accomplished, as it is not of necessity accompanied with any preparatory adjustments.

The lamp rods 12 are connected with the electric conductors 18. The rods may be tubular, in which case the conductors will extend therethrough up to the lamp socket.

In the operation of the device, the negative is placed upon the ground glass. Access is then had to the light compartment 8 through the hinged door 7, and the lamps may then be adjusted to any position to effect the desired result in the printing operation, as has been heretofore pointed out, and these positions may be changed at will in accordance with the character of the negative from which the picture is printed.

Having thus described my invention, what I claim and desire to secure by Letters Patent, is:-

1. In a photographic printing apparatus, a case having means for holding a negative and a sensitized element, and a plurality of lamps in the case, each lamp having a universal adjustment independent of the other lamps.

2. In a photographic printing apparatus, a case, a pair of lamps mounted in the case, one of said lamps having a universal adjustment independent of the other lamp.

3. In a photographic printing apparatus,

a case, a lamp-support in the case, a lamp adjustable in said support, and a spring pressed pin in the lamp-support to hold the lamp in its adjusted positions.

4. In a photographic printing apparatus, a case having means for holding a negative and a sensitized element, and a lamp in the case having a ball and socket joint.

5. In a photographic printing apparatus, a case having means for holding a negative and a sensitized element, a partition in the case having a socket, a lamp in the case supported in the socket and having a universal adjustment therein.

6. In a photographic printing apparatus, a case having means for holding a negative and a sensitized element and also having a light compartment, and a lamp mounted in said compartment and having a universal movement with respect to the negative.

7. In a photographic printing apparatus, a case having means for holding a negative and a sensitized element, a partition in the case having a socket, a lamp-supporting member movably mounted in the socket, and means on the partition and engaging the supporting member to prevent displacement of the latter.

8. A photographic printing apparatus having means for holding a negative, a partition in the case constituting the bottom of a light compartment and provided with a socket, a lamp-supporting member mounted in the socket and adapted to be adjusted therein, means for maintaining it in its adjusted positions, and a lamp adjustably connected with said supporting member.

9. In a photographic printing apparatus, a case having means for holding a negative therein, a light compartment having a socket formed therein, a spherical lamp-support loosely fitted in the socket, a lamp rod piercing said spherical support and adjustable longitudinally therein, and means carried by the spherical support to maintain the rod in its adjusted position.

10. In a photographic printing apparatus, a case having means for holding a negative therein, a partition in the case having a socket, a spherical member loosely fitted within the socket, means engaging said member to hold it within the socket and prevent accidental displacement thereof, a lamp-rod piercing said member and adjustable relative to the negative, a lamp supported upon the rod, and a spring-pressed pin mounted in the spherical member and adapted to engage the rod to hold it in its adjusted position.

11. In a photographic printing apparatus, a case having means for holding a negative and a sensitized element and also having a light compartment, lamps adjustably mounted in the compartment, supporting elements for the lamps, one of said supporting ele-

ments being adjustable in the other element and having its axis traversing the axis of said other element.

12. In a photographic printing apparatus, 5 a case having means for holding a negative and a sensitized element, and also having a light compartment, a lamp adjustably mounted in the light compartment, a rotatable supporting member for the lamp, and a 10 connecting member carried by the rotatable member and movable longitudinally in directions at right angles to the movements of the rotatable member.

13. In a photographic printing apparatus, 15 a case having means for holding a negative and a sensitized element and also having a light compartment, a lamp adjustably mounted in the light compartment, a rotatable supporting member for the lamp, a connecting member for the lamp carried by the 20 rotatable member and having its axis traversing the axis of said rotatable member, substantially as specified.

14. In a photographic printing apparatus, 25 a case having means for holding a negative and the sensitized element and also having a light compartment, a lamp disposed in the compartment, a ball and socket mounting for the lamp and yieldable elements engaging 30 the balls.

15. In a photographic printing apparatus, a case having means for holding a negative

and the sensitized element and also having a light compartment, a lamp disposed in the compartment, a ball and socket mounting for 35 the lamp, whereby the lamp may be adjusted, and yieldable elements engaging the ball to hold the lamp in adjusted positions.

16. In a photographic printing apparatus, a case having means for holding a negative 40 and the sensitized element, a lamp disposed in the case, and spring controlled means for holding the lamp in adjusted positions.

17. In a photographic printing apparatus, a case having means for holding a negative 45 and the sensitized element, a lamp disposed in the compartment, a ball and socket mounting for the lamp, means for adjusting the lamp with respect to the ball, and spring controlled means for holding the ball in different positions in its socket.

18. In a photographic printing device, the combination with negative and paper holding means, of a plurality of actinic lights, and means for varying the respective actinic 55 lights in their relation to the negative, whereby the intensity of light on various portions of the negative may be varied.

In testimony whereof I affix my signature, in presence of two witnesses.
